UNITED STATES PATENT OFFICE.

BERT HART AND THOMAS R. HOLNESS, OF WATERTOWN, NEW YORK.

WATER-HEATER.

1,250,867.

Specification of Letters Patent. Patented Dec. 18, 1917.

Application filed February 6, 1917. Serial No. 146,950.

To all whom it may concern:

Be it known that we, BERT HART and THOMAS R. HOLNESS, citizens of the United States, residing at Watertown, in the county 5 of Jefferson and State of New York, have invented new and useful Improvements in Water-Heaters, of which the following is a specification.

This invention relates to stoves and furnaces, and more especially to water heaters employing gas as the fluid fuel; and the object of the same is to produce an improved form of water heater for attachment to any domestic faucet and gas tip, from which 10 water can always be drawn hot, which if left standing with the gas lighted will do no injury to the device or to its surroundings, and which on occasions may be used for cooking of heating purposes.

These and other objects will be explained in the following specification, reference being had to the drawings wherein:—

Figure 1 is a central vertical sectional view of this entire device.

Fig. 2 is a plan view showing the same connected up with a faucet and a source of gas apply and with one of the dampers closed and the other partly opened.

Fig. 3 is a horizontal section on the line 30 3—3 of Fig. 1.

Fig. 4 is a bottom plan view.

Devices of this type have been commonly employed for domestic service where they were intended for connection with at least 35 some degree of permanency with the water system and the gas system of the household. Their attachment made it advisable to employ the services of an expert, and in some communities municipal supervision and per- 40 mit is necessary. We have devised a water heater of this character which any one can attach to any ordinary household spigot or faucet, which may be stood on the stove, or on a table, whose gas line may be slipped

45 over the ordinary gas nipple (the lava tip being preferably first removed), and which does not require the services of an expert or the attention of the householder. Many of its parts are those which may be pur- 50 chased in the open market, and therefore they may be replaced when they are damaged or destroyed. Its simplicity is a feature of advantage, and the possibility that like cooking or warming may be done upon 55 the device also commends it to the public.

Referring now to the drawings, we have

used the letter F to designate an ordinary spigot or faucet, and C any common form of coupling which may be attached to the faucet, assuming that the latter has a threaded nozzle. In like manner the letter H designates a gas line such as a flexible hose or rubber tube whereof one extremity may be slipped over a burner tip T whose lava member should be first removed. Thus the 60 flow of water can be controlled by the faucet, and the flow of gas by the key in the burner or wall bracket. The other end of the hose is connected with the gas supply system of our invention, and the same is illustrated 65 herewith as comprising an ordinary valve V if one is desired, an air mixer M, proper couplings and pipes P, and two gas burners B. All these may be and by preference are 70 ordinary gas elements which may be purchased in the open market and connected by a person not necessarily skilled in the art, as it is well known that the plumbing for manufactured gas need not be connected up 75 as carefully and closely as water plumbing, 80 and a little white lead inserted in any screw-threaded connection will suffice to retain the gas pressure. If a special form of burner is used at B, better results may follow, but the details of construction of this and other 85 elements which are lettered on the accompanying drawings form no part of the present invention. Also, while we have shown 90 the gas line pipe P beyond the mixer M as branched into two arms and led to two burners B, it will obviously be quite possible to branch this pipe and lead it to three or more burners if a larger size of water heater is desired; and therefore, whereas we have 95 described our invention and shown it as having but two flues, we do not wish to be limited in this respect.

Surrounding each burner is an upright flue numbered 1 in Fig. 1 and composed of inner and outer concentric shells or tubes 2 and 3 having an annular water space or jacket 4 between them, the same being closed at its upper and lower extremities by rings 5 and 6. Within the lower ring and the lower end of the inner tube is a spider 7 whose center incloses the gas pipe P whereby the flue as a whole is centered around the pipe and the burner. Within the upper ring 5 is a damper broadly indicated by the numeral 8 and having a handle 9 by which it 105 may be opened or closed as best seen in Fig. 2. The mixture of gas and air flows 110

through the pipe P to the burner B, and burns at the outlet of the latter in connection with air that flows upward through the spider and through the flue, the products 5 of combustion passing through the damper when the latter is opened or being retained in the flue; and it is obvious that articles and receptacles of proper size may be stood upon the upper end of the flue or placed 10 upon the damper plate and heated or perhaps cooked thereon. If a group of perhaps three or four of these flues were employed, it is possible that a good sized receptacle might be placed over the upper ends 15 of all of them, and food therein cooked from the combined heat from the several burners. If the valve V be employed the flow of gas may be regulated at this point instead of or in addition to its regulation 20 at the key of the burner tip or bracket.

Connected with the coupling C is a hose pipe 10 of sufficient length to lead from the nearest available faucet F to this device, and the hose is attached to an inlet pipe 11 25 which need not be larger than one-quarter inch with a heater of ordinary size. This inlet pipe enters shell 2 at a point 12 which is by preference somewhere near the lower end of the first jacket, so that the cold 30 water is led into this jacket immediately around its burner and receives the greatest amount of heat from the latter. Therein the water rises until it overflows at the point 13, and flows then through a pipe 14 35 to a low point 15 in the next jacket where again it receives heat from the burner therein. Within this jacket it rises again, and so on, throughout the several flues and jackets. The overflow is at 16 to an outlet pipe 40 17 which need not have a faucet, but may have one if desired. Thus the course of the water is from its inlet 11 where it is cold, to the lower end of the first jacket and upward therein, thence out of this jacket 45 at 13 to a low point 15 in the next jacket, thence upward within this jacket to a point 16 and out at the outlet 17; and the result is that hot or warm water may always be drawn from the point 17 because it has been 50 warmed by at least two burners, and when it is withdrawn from a second jacket, water that has been preliminarily heated in the first jacket flows into the second jacket to replace that drawn out. Hence if the 55 burners are turned on so that they emit but a small blaze, warm water may always be drawn at the outlet 17; and if they are turned up so that considerable heat is generated, hot water may always be drawn, but 60 in no event will cold water flow out the outlet 17 if the burners are lighted at all. It is quite obvious that, as above suggested, with more than two flues the efficiency of the de-

vice would be increased and its possibilities amplified. We do not wish to be limited in 65 this respect, nor as to the sizes, proportions, materials and exact details of construction.

Any suitable means may be provided for supporting this heater, and as shown herein we have employed a stand consisting of 70 a base 20 whose standards 21 are connected with the spiders 7, the latter in turn supporting the gas connections and flues and water connections. For bracing the parts it might be wise to employ a member 75 best seen in Fig. 3, and which may be cast or stamped in two parts and finally connected by rivets or bolts 22. The member includes large loops 23 which embrace the flues 1, and a small central loop 24 which 80 embraces the pipe between the valve V and mixer M, and by tightening up on the bolt 22 the several loops will be caused to clamp the parts which they embrace. In a very large sized device this bracing member 85 might be repeated or duplicated above the valve V, but we do not consider it necessary to show the same.

What is claimed as new is:—

1. In a water heater of the class described, 90 the combination with a pair of upright flues, water jackets around them, means for circulating water through the jackets, and means for controlling its flow; of gas burners disposed respectively in the lower ends 95 of the flues, a gas supply pipe between said flues and branched below them to the burners, spiders on the branches and within the flues, a stand supporting said spiders, and a clamping member having large loops surrounding the flues and a smaller interposed loop surrounding the gas supply pipe, for 100 the purpose set forth.

2. In a water heater of the class described, 105 the combination with a pair of upright flues, each surrounded by a water jacket, means for admitting cold water to the lower end of one flue, conducting it from the high end thereof to the lower end of the next flue, and permitting it to flow out of the 110 high end of the last-named flue, and means for controlling the flow of water; of gas burners disposed respectively in the lower ends of the flues, means for supplying gas thereto and controlling its flow, a spider in 115 the lower end of each flue through which the burner-pipe passes, a stand for supporting said spiders, and a clamping member having large loops surrounding said flues and a smaller interposed loop surrounding 120 the gas line, for the purpose set forth.

In testimony whereof we affix our signatures.

BERT HART.
THOMAS R. HOLNESS.
